COMBINATION KITCHEN CABINET AND TABLE

Wallace G. Palmer, Jr., Rochester, N. Y.

Application January 17, 1947, Serial No. 722,625

2 Claims. (Cl. 312—160)

1

This invention relates to a cabinet, more particularly for kitchen use, and has for its purpose to afford a structure occupying a minimum floor space and adapted to function both as a storage cabinet and as a table of sufficient size to permit serving a meal to four persons.

More particularly, the invention has for its object to afford a cabinet with a fixed table portion that is always available for use and a movable table portion that is positionable adjacent to the fixed table portion to constitute an extension and enlarge the fixed table portion when needed for serving, or positionable vertically in spaced relation above the fixed table portion in such position as to function as a closure for an upper storage compartment while exposing and permitting access at all times to a lower storage compartment just above the fixed table portion.

A further purpose of the invention is to afford a simple and efficient structure enabling such a cabinet to be manufactured from wood at a low cost, and which results in a sturdy, rigid, and durable construction.

Still another object of the invention is to provide a cabinet with a movable table portion so mounted on pivoted supporting arms that it can be swung instantly to either vertical or horizontal position and is rigidly supported when functioning as an extension for the fixed table portion, and which when in vertical position is held in position to serve as a closure for a compartment in which dishes, glassware, or the like may be arranged, while at the same time permitting access to the fixed table portion and the storage compartment thereabove.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in front elevation of a cabinet constructed in accordance with a preferred embodiment of the invention and showing the movable table portion in vertical position;

Fig. 2 is an end elevation of the same;

Fig. 3 is a view in front elevation, with the movable table portion in horizontal position;

Fig. 4 is an end elevation showing the movable table portion in the same position as Fig. 3;

Fig. 5 is a plan view showing the movable table portion in the same position as in Figs. 3 and 4;

2

Fig. 6 is a vertical sectional view on the line 6—6 of Fig. 3;

Fig. 7 is a view in end elevation illustrating a modified arrangement of the invention, and showing the movable table portion in vertical position;

Fig. 8 is a view in front elevation of the same;

Fig. 9 is a view in end elevation of another modification, with the movable table portion in horizontal position, and

Fig. 10 is a plan view of the same.

Referring more particularly to the drawings in which like reference numerals refer to the same parts throughout the several views, and to Figs.

15 1 to 6 inclusive, 1 designates the side walls of a cabinet, 2 designates a rear wall, 3 is a fixed table portion secured between the side walls 1 and rear wall 2 and extending forwardly preferably beyond a front wall 4, which affords a storage compartment beneath the fixed table portion 3, the latter storage compartment being accessible through doors 5 and preferably including a shelf 6 attached to the rear wall 2 and side walls 1. It will be understood that the fixed table portion 3 which may be of any desired depth is rigidly fastened to the side walls 1 and rear wall 2, and arranged in spaced relation above the fixed table portion 3 is a shelf 7 affording a lower storage compartment just above the fixed table portion 3 for receiving kitchen utensils, food-stuffs, dishes, glassware, or the like. 8 designates a second shelf in spaced relation above the shelf 7, affording an upper storage compartment for holding dishes or glassware.

35 The side walls 1 above the fixed table portion 3 are of reduced width, as usual in kitchen cabinets, to afford a readily accessible and sizeable work space on the fixed table portion 3, and it is desirable to provide an extension for the fixed table portion to afford a large rigid table that can be utilized when serving a meal, without interfering with the normal use of the fixed table portion and the lower storage compartment thereabove, and in order to accomplish this, there 45 is provided a movable table portion 9 that is positionable horizontally adjacent to the fixed table portion, as illustrated in Figs. 3 to 6 inclusive, or vertically in spaced relation above the fixed table portion and adjacent to the front of the upper storage compartment, functioning as a closure therefor, as shown in Figs. 1 and 2.

To this end, there are provided supporting arms 11, the inner ends of which are pivoted at 12 to the side walls 1. The supporting arms 11 are preferably in the form of wooden strips as

shown, their inner ends being angularly cut at 13 and when in vertical position abutting the corresponding angular surfaces 14 on the stationary vertical strips 15 which are attached to the side walls 1. The movable table portion 9 is fixedly secured between the outer ends of the supporting arms 11, as shown, while 16 designates a shelf portion secured against the table portion 9 between the supporting arms 11 and located between the front and rear edges of the movable table portion 9 and adjacent to the outer surface thereof.

The shelf portion 16 affords a strengthening and bracing means whereby a rigid relationship is maintained between the supporting arms and the movable table portion 9, such that when the supporting arms and movable table portion are swung to horizontal position with the table portion 9 adjacent to the fixed table portion 3, the movable table portion is firmly and rigidly held and constitutes for all practical purposes a continuation of the fixed, rigid table portion 3. Movement of the supporting arms downwardly is limited by the blocks 17 fastened to the side walls of the cabinet, as shown, and positioned so as to engage the adjacent edges of the supporting arms when the latter reach a horizontal position, as shown in Figs. 3 to 6 inclusive.

With this arrangement, it will be observed that when the movable table portion 9 is in its uppermost position, it acts as a closure for the upper storage compartment, as shown in Fig. 1, and at the same time the fixed table portion 3 and the lower storage compartment immediately thereabove are accessible and available for use. When it is desired to enlarge the table for serving purposes, the movable table portion is swung downwardly until the supporting arms engage the blocks or stops 17, in which position the table portion 9 lies adjacent to the front edge of the fixed table portion 3 and forms a continuation thereof, providing a table of sufficient size to serve four persons. 18 designates a spring catch secured to the upper shelf 8 for holding the movable table portion in its vertical position, while 19 designates an electric socket that may be provided on the rear wall 2 at the back of the lower storage compartment.

Referring to Figs. 7 and 8, the invention may be incorporated in a cabinet in which the lower part is of the same depth as the upper part, with the side walls cut away as at 21, see Fig. 7, and the fixed table portion 22 of less depth than in the previously described form. With such arrangement, the movable table portion 23 is preferably mounted between the outer ends of metal supporting arms 24 which have their inner ends curved and preferably offset from the outer ends, as shown in Figs. 7 and 8, and pivotally supported on the side walls of the cabinet as at 25. With this arrangement, when the movable table portion 23 is in its vertical position, it acts as a closure for the upper storage compartment, while the lower storage compartment and fixed table portion are exposed and accessible, and when it is desired to enlarge the table, the movable table portion 23 is swung downwardly to a horizontal position where it lies adjacent to the fixed table portion 22. With this arrangement, the metal

supporting arms 24 rest on the stops 26 when in horizontal position.

It may be desirable, in order to facilitate use of the extended table, to provide additional leg room under the fixed table portion, and in order to accomplish this objective, the lower part of the cabinet beneath the fixed table portion 28 may be cut away, or constructed at the front with angular corners 27, see Fig. 10, instead of having 10 right-angled corner portions as in the construction shown in Figs. 1 to 6, and by forming the lower part of the cabinet beneath the fixed table portion 28 with such angular corners, additional leg room is afforded under the table facilitating the serving of four people around the table when necessary. With this construction, the supporting arms 29 are extended at their inner ends beyond their pivotal points, as indicated at 31, and stops or blocks 32 are secured to the side walls 33 in position to engage the inner surfaces of the rear ends 34 of the supporting arms and limit upward movement of the latter, so as to hold the movable portion firmly and solidly when arranged horizontally and serving as an extension to the fixed table portion 28.

While the invention has been described with reference to certain specific embodiments, it is not restricted to the details herein disclosed, and this application is intended to cover such modifications or departures as may come within the purposes of the improvement or the scope of the following claims.

I claim:

1. A cabinet comprising side walls and a fixed table portion, the side walls being cut away at their front edges above the fixed table portion, curved metal supporting arms pivoted at their inner ends to said side walls in rear of said cut-away portions, and a movable table portion 40 mounted between the outer ends of the supporting arms and positionable horizontally adjacent to said fixed table portion or vertically in spaced relation above the fixed table portion.

2. A cabinet comprising side walls and a fixed table portion, the side walls being cut away at their front edges above the fixed table portion, a shelf spaced above the fixed table portion affording a lower storage compartment, a second shelf spaced above the first mentioned shelf affording an upper storage compartment, curved metal supporting arms pivoted at their inner ends to said side walls in rear of said cut-away portions, and a movable table portion mounted between the outer ends of the supporting arms and positionable horizontally adjacent to the fixed table portion or vertically adjacent to the front of said upper storage compartment, the lower storage compartment being at all times exposed and accessible.

WALLACE G. PALMER, JR.
